(57) **CLAIM**

The ornamental design for a portable label printer, as shown and described.

DESCRIPTION

FIG. 1 is a front, right and top perspective view of a portable label printer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, left and bottom perspective view thereof; and,

FIG. 9 is a rear, left and top perspective view thereof. The broken lines immediately adjacent to the claim depict the bounds of the claimed design, while all other broken lines are directed to environment. The broken lines form no part of the claimed design.

1 Claim, 9 Drawing Sheets
